UNITED STATES PATENT OFFICE.

FRANK W. ROBINSON, OF READING, PENNSYLVANIA, ASSIGNEE TO THE NOLDE & HORST CO., OF READING, PENNSYLVANIA, A CORPORATION OF PENNSYLVANIA.

CIRCULAR-KNITTING MACHINE.

1,262,568.

Specification of Letters Patent. Patented Apr. 9, 1918.

Application filed February 19, 1916. Serial No. 79,378.

To all whom it may concern:

Be it known that I, FRANK W. ROBINSON, a citizen of the United States, residing at Reading, in the county of Berks and State 5 of Pennsylvania, have invented certain new and useful Improvements in Circular-Knitting Machines, of which the following is a specification.

My invention relates particularly to seam-10 less-hosiery knitting machines; and my main object is to provide a mechanism adapted to continuously and automatically produce drop-stitch stripes upon the entire leg and upper-foot portions as may be de-15 sired, in connection with the usual reciprocatively-knitted heel and toe, and solid-bot-20 tom foot portions, and with or without additional lengthened-loop effects in determined courses; as fully described in connec-25 tion with the accompanying drawing illus- trating a preferred embodiment of the com- plete invention and the novel features of which are clearly defined in the claims.

Figure 1 is an elevation showing portions 25 of a known form of circular knitting machine having the several features of my invention applied thereto in connection with preferred operating mechanism therefor.

Fig. 2 is a corresponding elevation taken 30 at right angles to Fig. 1.

Figs. 3 and 4 are separate views of the ratchet-toothed counting wheel for spacing the lengthened-loop courses.

Fig. 5 is a diagrammatic view of the cam-35 ring employed; separate dotted lines indicating the several paths taken by the different needles during the regular knitting of the leg courses.

Fig. 6 is a plan view of the cam ring 40 showing the additional cams employed and means for operating them.

Fig. 7 is a detail elevation, looking in the direction of arrow 7 Fig. 6.

Fig. 8 is a diagrammatic view indicating 45 the arrangement of the differently hubbed needles in the needle cylinder.

Figs. 9 to 12 indicate the differently formed needles employed, and Fig. 13 indicates a product of my improved machine.

The machine indicated is of the so-called 50 Banner type employing a rotary needle cylinder 2 provided with a circle of needles to which vertical movement is imparted by a fixed cam ring 4. The shaft 5 is employed 55 for rotatively or reciprocatively driving the

needle cylinder, and the usual knitting operations are controlled by the pattern chain 6 and cam drums on shaft 7.

The needle movements as commonly provided, produce the leg portion of the stocking and the intermediate foot portion, by circular knitting employing the whole circle 60 of needles, while the heel and toe portions of the foot are produced by reciprocative knitting employing the approximately half- 65 circle of rear needles only. This division of the circular series of needles is usually provided for as indicated in the drawings, by making the cam-engaging butts of the needles of different lengths; the half circle 70 for knitting the front of the tubular stocking having long butts as indicated in Fig. 9, while those which produce the rear half of the tubular stocking and the heel and toe 75 portions are provided with short butts as indicated in Fig. 10.

My invention provides for producing lengthwise drop-stitch stripes as indicated in Fig. 13, during the usual automatic knitting; these being spaced around the entire 80 circular portion of the leg part of the stocking and on the upper portion only of the foot part. For the front half of the stocking, where the drop stitch stripes are to appear on both the leg and the foot, the corresponding needles will not be required at all and may therefore be removed from the cylinder; but in the rear half circle of needles all will be required and must be retained. To provide for separately actuating those 90 that need to be operated so as to cause drop stitch effects in one portion and solid effects in another portion of the circular knitting, I make the cam-engaging butts of these retained drop-stitch needles, 12, 12^a Figs. 11 95 and 12, of a length intermediate that of the long butt needles 10, Fig. 9, and the short- butt needles 11 Fig. 10.

Fig. 8 indicates diagrammatically an arrangement of needles in the needle cylinder 100 adapted for producing a series of drop stitch effects; 10 representing the long butt needles making up one half of the circular series, and 11, 12 the shorter butt needles arranged in the other half. A two-needle 105 drop-stitch is provided for in the front half by removing certain of the long-butt needles while among the short-butt needles 11 are spaced pairs of drop stitch needles 12, 12^a having butts of a length intermediate the 110

length of the long and short butt needles 10 and 11. These needles 12 must be so actuated as to cause them to avoid knitting during the knitting of the leg portion of 5 the stocking and to throw them into knitting action when the heel is reached and retain them in action in co-operation with the short butt needles 11, during the knitting of the remaining portion of the stocking.

10 Fig. 5 indicates diagrammatically the cam cylinder of a machine embodying my improvements, developed in a flat plane and looking at the inner face thereof. As 15 shown, 15 represents the top center cam, 16 the bottom center cam, 17 the right stitch cam, 18 the left stitch cam, and 19 the needle rest. The travel of all the needles during 20 the circular knitting operation, is normally as indicated by the middle dotted line 20 which represents the line of needle butts; that is from the needle rest 19, up right 25 stitch cam 17, under top center cam 15 under left stitch cam 18 and back to needle rest 19. When my drop stitch needles 12 are employed 30 however, they must be moved out of knitting action during the knitting of the leg portion of the stocking. To accomplish this I provide a drop stitch cam 25 which may be adjustably set into the path of the 35 needle butts, as shown in Fig. 6, far enough only to engage the intermediate butt needles 12 without engaging the short butt needles 11; the effect of this adjustment of said cam 25 being to lower these drop stitch needles 40 12 to get them out of knitting action by passing them under the right stitch cam 17, under bottom center cam 16, under left stitch cam 18 and back to needle rest 19 where they are again aligned with the short 45 butt needles, which path of travel is indicated in Fig. 5 by the lower dotted line 22. The cam 25 however, when thus set into the path of the needle butts sufficiently to engage the intermediate butt needles 12, could 50 also act upon all the long butt needles 10 employed in making the tubular portions of the stocking if allowed to, and I therefore provide a special separating cam 26 for these needles, which is movable toward and 55 away from the path of the needle butts as shown in Fig. 6. In knitting the leg portion of the stocking this separating cam 26 is advanced only so far as to engage the long butt needles 10 and avoid both the intermediate and short butt needles; the result being that all the long-butt needles are elevated sufficiently to clear the drop stitch cam 25; a fixed leveling cam 27 being provided for again lowering them after they 60 have passed the cam 25 so that they will then contact with the right stitch cam 17 and follow the regular stitch course; their line of travel over the drop-stitch cam and through the regular stitch course being indicated by the top dotted line 21.

The drop-stitch cam 25 is so mounted that it may be withdrawn from the path of the needle butts, which will permit the intermediate butt needles 12 to ride up the right stitch cam 17 with the short-butt 70 needles 11. I have found however that where the drop-stitch needles are used in pairs or more, there is a tendency for them to fail to pick up the thread with regularity, causing defective knitting. To overcome 75 this I have provided that one of each pair or group of drop stitch needles 12^a shall be provided with a long latch as indicated in Fig. 12. This latch is of a length sufficient to prevent it clearing the previous loop when 80 the needle is raised by the right-stitch cam 17, the top portion of the latter being cut away as indicated at 17^a so that while the regular latch needles will rise sufficiently to 85 clear their latches the long latch needles 12^a will not clear but will "tuck" or gather several layers of yarn. This tucking I arrange 90 will occur several courses before the heel is reached; and just before the long latch needles are raised out of action for the reciprocal knitting of the heel, the cam 26 is moved still farther into the path of the 95 needle butts so that it will actuate both long and intermediate butt needles. The effect then is that both long and intermediate butt 100 needles will follow the path indicated by the top dotted line 21, and the cam 26 is of such a height that it will raise the long latch needles sufficiently to clear their latches and end the tucking action of the latter. 105

The cam 26 is retained in this innermost position during the remaining knitting operation of the stocking. The fixed cam 27, it will now be observed merely lowers the needles to the stitch cam 17, but their latches 105 have already been cleared by the cam 26.

The long butt needles 10 are raised out of action for the heel portion, this being accomplished by the usual dividing cam 30; the face 30^a of the latter however being in 110 the present construction cut back to avoid raising the intermediate butt needles 12. After the heel is completed, by the usual reciprocal narrowing and widening, the long butt needles are again thrown into 115 knitting position by the cam 31, the latter being preferably mounted as usual on a vertical stem with the cam 30, so that one or other may be placed in position.

The circular knitting for the foot portion 120 of the stocking is as usual, except that the cam 26 causes the needle butts to follow the path indicated by dotted line 21. The drop stitch stripes which are formed by removing certain of the long-butt needles, continue through the top portion of the foot, while the withdrawn cam 25 permits the intermediate butt needles 12 to operate with the short butt needles 11 to knit a solid fabric for the bottom portion of the foot. 130

The toe portion of the stocking is made in a manner similar to the heel, except in this case no tucking is required as no drop stitch stripes are being formed.

In addition to the usual operating mechanism, means are required for properly actuating the cams 25 and 26. Cam 25 is mounted on a stem 40 having a head 41, and is normally held in the path of the needle butts against the action of a retracting spring 42, by a latch 43 at the top of a post 44. The cam 26 is similarly mounted on a spring retracted stem 45, the latter having a head 46. A vertically movable rotative shaft 50, mounted at the side of the knitting standard and actuated as hereinafter described, has an arm 52 (see Fig. 6) adapted to contact with the head 46 of the stem 45; and said arm has an extension 53 arranged to swing under the post 44 of the latch 43. The cam 25 may be moved into the path of the needle butts by operation of the stem 40 through the head 41, when beginning a stocking and is automatically withdrawn at the point of tucking, just prior to the knitting of the heel, by a vertical movement given to the shaft 50. A rotary or turning movement of the shaft controls the projection of the cam 26 into the path of the needles, and I preferably provide the arm 52 with adjustable stops in the form of set screws 54 and 55 to correct any inaccuracy in the cam which imparts turning movement to said shaft 50.

The shaft 50 is mounted in brackets 60 secured to the frame as shown, which support it in adjusted position relative to the cam shaft 7. A cam disk 70 on the latter is formed with a tit 71 on its circumferential face 72, which tit contacts with a rollered arm 73 fixed to the shaft 50 and raises the latter, against a spring 74, so as to cause retraction of the cam 25 by releasing the latch 43. A turning movement is imparted to the said shaft through a rollered arm 75 secured thereto and riding upon the face of said disk 70; the latter being provided with a cam track adapted to, first, rotate said shaft 50 sufficiently to cause the cam 26 to enter into the path of the needle butts only far enough to actuate the long butt needles; and second, to move it farther into the path of the needles far enough to engage both long and intermediate butt needles, but not short butt needles. This cam disk 70 is operated with the cam shaft 7, which latter is controlled by the pattern chain 6, and is timed and shaped to perform its operations in harmony with the regular knitting operations of the machine.

Another object of my invention is to provide for making loose or lengthened-loop courses in the circular knitting, in connection with the drop-stitch stripes, thereby producing an ornamental block effect. The

cam ring 4 is so mounted as to be vertically adjusted to determine the length of loops drawn by the needles, this being commonly required in changing yarns. This vertical adjustment of the cam ring is accomplished as heretofore by mounting it upon a vertical bar 80 and effecting the movement of said bar by cam disks 81, 82 (Fig. 2) on the drum shaft 7, acting through an arm 83 on said bar. These disks 81, 82 control the movement of the bar only at the time of a change of yarn, and I must therefore provide other means to actuate it at determined intervals so as to intermittently produce loose circular courses 150 extending across the vertical drop-stitch stripes 151 as indicated in Fig. 13. These additional means comprise an extension 90 of said arm 83, the rollered end 110 of which rests upon a cam disk 91 rotatably secured to the frame 85 standard and having its edge formed with depression 92 arranged for lowering said bar 80 at determined intervals. The rotation of the cam disk 91 is effected through a ratchet-toothed wheel 93 thereon (see Figs. 3 and 4), which latter is operated by a pawl 94 mounted upon an eccentric on the drive shaft 5. The number of teeth provided in the ratchet wheel 93 determine the number of courses ordinarily knitted between the loose or lengthened-loop courses, the wheel as shown making two of the latter for each revolution. A pattern controlled arm 95 pivoted to the frame at 96 contacts with said pawl to move it out of engagement with the ratchet teeth, the opposite extension 97 of said arm 95 riding upon a cam disk 98 on the shaft 7 which controls its movement. The ratchet wheel is formed with a deep tooth 99 so that it may always be brought to rest after a determined rotation, while a high-tooth 100 insures against its ever coming to rest with the arm-extension 90 in a depression 92, which would produce a contiguous lengthened loop course. It may be desired to effect or to preserve additional lengthened loop courses at times when the cam shaft 7 is at rest, and I therefore provide a shaft 105 having an extension 106 projecting under the pawl controlling arm 97, and another extension 107 set in the path of the pattern chain 6, which latter may be provided with properly spaced studs 108 to actuate said pawl controlling arm 97.

The arm 83-90 is preferably provided with the roller 110 to insure its free movement over the rotated disk 91, and it is preferably pivotally connected at 111 to the bar 80 and provided with an adjustable contact 112 with the side of said bar to accurately regulate the drop of the bar 80 for forming the loose courses, instead of determining such drop by the depth of the depressions 92 in disk 91.

The complete mechanism specifically described and shown may be readily varied as required for application to circular knitting machines in which the rotary motion is imparted to the cam ring instead of to the needle cylinder, and be otherwise modified in detail construction, without departing from the essentials of my invention as particularly pointed out in the claims.

10. What I claim is:

1. A seamless hosiery knitting machine comprising a circle of single-butt needles made up of an approximately half-circle series having long butts and an approximately half-circle series some of which have short-butts and others medium-butts, and needle-operating mechanism comprising cams directly operative upon said butts adapted to throw said medium-butt needles 15 out of action for forming drop stitches and to automatically throw them into action for regular knitting.

2. A seamless hosiery knitting machine comprising a circle of needles made up of an approximately half-circle series having long butts and an approximately half-circle series some of which have short-butts and others medium-butts, and needle-operating mechanism comprising means for successively raising said long-butt needles only, lowering said medium-butt needles only, and bringing said raised long-butt needles 20 into co-operative relation with the short butt needles preliminary to each loop-forming operation.

3. A seamless hosiery knitting machine comprising a circle of needles made up of an approximately half-circle series having long butts and an approximately half-circle series some of which have short-butts and others medium-butts, and needle-operating mechanism comprising means arranged to operate during successive courses of knitting to raise said long-butt needles only, to lower 25 said medium-butt needles only, and to bring said raised long-butt needles into co-operative relation with the short-butt needles preliminary to each loop-forming operation.

4. A seamless hosiery knitting machine comprising a circle of single-butt needles made up of an approximately half-circle front series with long butts for circular knitting only, and an approximately half-circle rear series certain of which have short butts and others of which have medium length butts adapting them for independent operation as drop-stitch needles; and needle-operating mechanism comprising means successively operative upon the different-length butts in successive courses for temporarily separating said front series of needles and for throwing said drop-stitch needles out of knitting action, during leg-knitting, and means for automatically throw-

ing said drop-stitch needles into action for 65 foot-knitting.

5. A seamless hosiery knitting machine comprising a circle of needles made up of an approximately half-circle series having long-butts and an approximately half-circle front 70 series some of which have short-butts and others medium-butts, and needle-operating mechanism comprising a dividing cam and a separating cam both operative upon said front series of needles only, and an adjustable drop-stitch cam operative upon said certain rear needles only to put them out of or into knitting action.

6. In a seamless hosiery knitting machine having a circle of needles made up of an approximately half-circle series having long butts and an approximately half-circle series some of which have short butts and others medium-butts; a needle-operating mechanism comprising a separating cam for 80 raising the long-butt needles, a drop-stitch cam for lowering the medium-butt needles, and a leveling cam for lowering the separated long-butt needles.

7. In a seamless hosiery knitting machine 90 having a circle of needles made up of an approximately half-circle series having long butts and an approximately half-circle series some of which have short butts and others medium butts; a needle-operating 95 mechanism comprising a separating cam for raising the long-butt needles, a drop-stitch cam for lowering the medium-butt needles, a fixed leveling cam for lowering the separated long-butt needles, and pattern-operated 100 means for successively operating said separating cam and drop-stitch cam.

8. In a seamless hosiery knitting machine having a circle of needles provided with cam-engaging butts of different lengths, a 105 needle-operating mechanism comprising an adjustable separating cam and an adjustable drop-stitch cam each directly operative upon different butts, a common operating shaft for said cams, and pattern-controlled 110 means for operating said shaft to successively actuate said cams.

9. In a seamless hosiery knitting machine having a circle of needles provided with cam-engaging butts of different lengths, a 115 needle operating mechanism comprising an adjustable separating cam, an adjustable drop-stitch cam, a common operating shaft for said cams, and pattern-controlled means for imparting successive turning and longitudinal movements to said shaft to successively actuate said cams.

10. In a seamless hosiery knitting machine having a circle of needles provided with cam-engaging butts of different lengths, a 125 needle-operating mechanism comprising an adjustable separating cam and an adjustable drop-stitch cam, each directly operative

upon different butts, a common operating shaft for said cams, and pattern-controlled means for imparting different turning movements to said shaft to differently adjust said separating cam.

11. In a seamless hosiery knitting machine having a circle of needles made up of an approximately half-circle series having long butts and an approximately half-circle series some of which have short butts and others medium-butts; a plurality of said medium-butt needles being grouped together and one thereof having a lengthened-latch; a needle-operating mechanism comprising a separating cam, means for automatically adjusting said cam to engage either the long-butt needles only or the long-butt and medium-butt needles, a drop-stitch cam, and a stitch-cam of less height than said separating cam.

12. In a seamless hosiery knitting machine having a circle of needles provided with cam-engaging butts of different lengths, a needle-operating mechanism comprising an adjustable separating cam and an adjustable drop-stitch cam, each directly operative upon different butts, a common operating

shaft for said cams, loop tensioning and loosening means, and pattern-controlled means adapted to coöperatively actuate said shaft and loop tensioning and loosening means substantially as set forth.

13. A seamless hosiery knitting machine, comprising a needle cylinder and a needle operating cam ring, one of which is rotatable and the other vertically adjustable, an approximately half-circle series of needles in said cylinder, having long butts, and a half-circle series some of which have short butts and others medium-butts, needle operating mechanism comprising cams directly operative upon said medium-butt needles to throw them out of action for forming drop stitches and into action for regular knitting, a supporting bar for said vertically adjustable member carrying a pivoted transverse arm, and pattern-controlled loop-tensioning and loosening means coöperatively acting upon opposite ends of said arm to produce determined extremes of tensioning, substantially as set forth.

In testimony whereof I affix my signature.

FRANK W. ROBINSON.
